I. L. AULT

VALVE SEAT REMOVING TOOL FOR PUMPS

Filed Jan. 29, 1924

Isaac L. Ault
INVENTOR.
BY John W. Spellman
ATTORNEYS.

UNITED STATES PATENT OFFICE.

ISAAC L. AULT, OF COMANCHE, OKLAHOMA.

VALVE-SEAT-REMOVING TOOL FOR PUMPS.

Application filed January 29, 1924. Serial No. 689,312.

To all whom it may concern:

Be it known that I, ISAAC L. AULT, a citizen of the United States, residing at Comanche, in the county of Stephens and 5 State of Oklahoma, have invented certain new and useful Improvements in Valve-Seat-Removing Tools for Pumps, of which the following is a specification.

This invention relates to improvements in 10 tools and refers more particularly to a valve seat gripping and removing tool.

The principal object of the invention is to provide a tool for use in removing worn and faulty valve seats in oil well and mud 15 pumps and varied classes of pumps or the like.

The invention is also designed with a view to its durability, ease of operation and economical manufacture, and in this connection 20 is also adapted to save considerable time and labor.

The new and improved valve seat lifting tool will be clearly understood by reference to the following description, taken in 25 connection with the accompanying drawings forming part hereof and in which:

Figure 1 is a side elevational view of the invention, one side of the housing being removed to reveal the interior.

30 Figure 2 is a detail view of the lower end or gripping portion of the tool.

Figure 3 is a top or plan view taken on line 3—3 on Figure 1.

Figure 4 is a detail view of the operating handle of the tool; and,

Figure 5 is a vertical sectional view of a pump and illustrating the invention in operative position thereon.

Continuing the description of the device 40 and referring to its various parts more in detail; the numeral 1 denotes a casing enclosing a series of pinion gears 2—2 and rollers 3—3 supported upon suitable pins as shown.

45 The casing 1 converges upward and forms a reduced end with an inner abutment 4. An opening in the abutment permits of the outward extension of a squared end sleeve 5 interiorly screw threaded and provided with 50 a shoulder 6 which retains the sleeve in position against abutment 4.

Within the casing 1 is a toothed bar 7, the upper end 8 of which is reduced in diameter and screw threaded for reception 55 into the sleeve 5, clearly shown in Figure 4. This bar 7 is in mesh on each side with the

pinion gears 2—2, previously referred to and these gears in turn co-act with a pair of puller arms 10—10 in connection with the rollers 3—3, the latter for the purpose of 60 retaining the toothed arms in alinement or mesh with the gears. The rollers 3—3 ride between the backs of the arms and a tracking 11 as the arms are operated.

Spaced between the lower ends of the 65 puller arms 10—10 is a valve seat gripping member consisting of two halved part 12—12 hinged together by a rod 13 which likewise holds the arms 10—10 to the parts 12—12. Between the halved parts 12—12 70 of the gripping member is a spring 14 for the purpose of providing outward tension on the parts 12—12 as they are pushed into the valve seat. These parts, as will be seen are rounded and are provided with shoulders 75 15—15 so that when pressure is applied, they ride past the valve seat A in pump B and are thus locked beneath its lower end.

From the above, it will be seen that the 80 tool may be inserted into the pump cylinder, and the sleeve 5 rotated which will force the valve seat gripping members into and beneath the valve seat until they spring out past the shoulders 15—15. The rotation of the sleeve is now reversed, causing the bar 7 85 and puller arms 10—10 to lift the seat.

It should be understood that modifications and changes may be made in the construction of the device in keeping with and within the scope and meaning of the following claims.

I claim—

1. In a device of the nature set forth; a pair of toothed arms, the upper ends movably arranged in a casing; valve seat gripping members carried on the lower ends of the arms; a toothed bar and pinion gears arranged to co-operate with the toothed arms; and a sleeve upon the toothed bar for moving the bar to operate the arms and 95 valve seat gripping members against a valve seat to remove the seat.

2. A valve seat removing tool for pumps or the like, comprising a casing, a pair of spaced puller arms with teeth on their inner 100 surfaces and movable within and depending downward from the casing and carrying valve seat gripping members; a bar having toothed sides and meshing with pinion gears disposed between the sides of said bar and 110 said arms; guide rollers between the arms and the casing; a sleeve upon the upper end

of the bar arranged so that when moved thereupon it will cause the valve seat gripping members to engage and remove the valve seat.

5. 3. A valve seat removing device for pumps or the like comprising a casing, arms depending therefrom; a bar with a sleeve co-acting with pinion gears and said arms to move the arms; valve seat gripping members carried on the lower ends of the arms;

said members being rounded and provided with projecting shoulders and under spring tension; said shoulders adapted to be projected beneath the valve seat when under pressure to engage the valve seat, the movement of the sleeve acting to loosen and remove the valve seat.

In testimony whereof I have signed my name to this specification.

ISAAC L. AULT.
